SMOKER'S KIT

Filed March 28, 1927

Fig. 5.

INVENTOR,
Joseph Battista,
By Minturn & Minturn,
Attorneys.

UNITED STATES PATENT OFFICE.

JOSEPH BATTISTA, OF INDIANAPOLIS, INDIANA.

SMOKER'S KIT.

Application filed March 28, 1927. Serial No. 178,899.

It is often the case that a person smoking is embarrassed by finding that there is no ash tray or similar receptacle present to receive the ashes and butts of the cigarette or 5 cigars smoked, and it is the purpose of this invention to supply a conveniently small and compact kit of such size that it may be carried in a pocket about the smoker's person, which kit may be brought out and utilized 10 as an ash and butt receiver and may then be closed, returned to the pocket, and emptied later at a more convenient place.

Such receptacle carries a device for snuffing out the lighted end of the cigarette, and 15 also a compartment to hold a small box of matches of the type well known as safety matches, the side of the box of which matches carries a strip of a chemically impregnated surface over which the match head is 20 scratched to ignite it.

The invention is described more particularly in reference to the accompanying drawing, in which

Fig. 1, is a fragmentary side elevation of 25 the kit with the lid partially opened;

Fig. 2, a top plan view of the kit with the lid opened back;

Fig. 3, a vertical section on the line 3—3 in Fig. 2;

Fig. 4, a vertical section on the line 4—4 in Fig. 2; and

Fig. 5, an end elevation of the kit opposite the hinged end of the lid.

Like characters of reference indicate like 35 parts throughout the several views of the drawing.

The kit is a box-like structure formed to have a bottom 10, a side wall 11 entirely along one side of the bottom; an end wall 12, 40 a side wall 13 from the wall 12 along the opposite side to about the center of the bottom 10; a partition wall 14 joining the end of the wall 13 across the bottom 10 to the side wall 11 parallel to the end wall 12; and 45 a front end wall 15 from the side wall 13 across the front of the bottom 10.

This construction leaves an opening between the front wall 15 and the partition wall 14 from one side only of the kit, and 50 the width between the two walls 14 and 15 is such that a box of matches (not shown) may be slipped therebetween rather tightly so as to be retained by friction.

The front wall 15 is provided with a long

window 16 therethrough and that part of 55 the side wall 11 lying between the walls 14 and 15 has a hole 17 therethrough so as to permit the smoker to insert a finger therein to push the box of matches to extend out of the kit from the other side, take a match 60 therefrom, and strike it through the window 16 on the side of the match box.

Within that section of the kit bounded by the end wall 12, the side walls 11 and 13, and the wall 14, a receptacle 18, shown as a cylindrical vessel open from the top, is secured to the bottom 10 and serves as a means for permitting a cigarette to be inserted therein and pressed against the bottom 10 to be forced downwardly in a rotating manner 65 70 so as to snuff out or extinguish the cigarette and thereby effectually prevent any annoying smoke to arise as would otherwise be the case were the unsmoked portion merely deposited in the kit. The section of the kit so 75 bounded as above described also serves as a receptacle to receive the ashes from the cigarettes and cigars as they are smoked.

A lid 19 is hinged along one edge to the top edge of the wall 12 so that the lid may be 80 folded down to form a cover over the entire top of the kit. Means for securing the lid in the closed position are provided by the spring tongue 20 extending from the lid 19 and the lip 21 pressed outwardly from near 85 the top of the wall 15, over which lip 21 the tongue 20 may yieldingly engage.

The two opposite sides of the lid 19 are turned back over the top face to form the inturned flanges 22 and 23 for the purpose 90 of permitting identification or advertising cards to be inserted thereunder.

Affixed to the inside, under face of the lid 19 are the cigarette holder 24 and the cigar holder 25, which two holders are presented 95 when the lid 19 is opened back as in Fig. 2. These holders merely serve as convenient places to receive the lighted cigarette or cigar so as to let the lighted end project out over the ash receiver of the kit.

I claim:

As a new article of manufacture, a box having a base, a rear wall along the base, a long side wall entirely along one side of the base, a short side wall extending from the 105 rear wall along only a part of the other side of the base whereby a match-box opening is provided for the sliding therethrough of a

match-box, said long side wall having a finger opening opposite the match-box opening, a wall extending across the base from the forward end of the short side wall to the 5 opposite side wall, a front wall along the base, and a lid hinged to the rear wall, a snuffer receptacle secured to the base back

of said wall extending across the base, and holders secured to the under side of the lid, said holders being spaced thereon to pass one 10 on each side of the snuffer when the lid is closed.

In testimony whereof I affix my signature.
JOSEPH BATTISTA.
